ADJUSTABLE BROACH HOLDER

Norman H. Iversen, Birmingham, Mich., assignor
to Production Broaching Corporation, Wayne
County, Mich., a corporation of Delaware

Application November 21, 1946, Serial No. 711,327

10 Claims. (Cl. 29—95.1)

1

This invention relates to adjustable broach holders and more particularly to a holder for adjustably mounting broach bars that are disposed radially with respect to a central axis for cutting splines, gears or the like.

The invention has for its object to provide means for simultaneously radially adjusting a series of angularly spaced broach bars.

A further object of the invention is to provide means associated with the broach bar adjusting means for indicating the amount of radial movement imparted to the bars.

A further object of the invention is to provide an adjusting device that is operable without releasing the bar clamping means.

With the above and other objects in view, the invention may be said to comprise the broach holder as illustrated in the accompanying drawings, hereinafter described and particularly set forth in the appended claims, together with such variations and modifications thereof as will be apparent to one skilled in the art to which the invention pertains.

Reference should be had to the accompanying drawings forming a part of this specification, in which:

Figure 1 is a side elevation of a broach holder embodying the invention;

Fig. 2 is a central vertical section through the broach holder, taken on the line indicated at 2—2 in Fig. 1;

Fig. 3 is a top plan view of the broach holder with portions of the cap broken away to show the assembly;

Fig. 4 is a fragmentary vertical section through the cap, taken on the line indicated at 4—4 in Fig. 3;

Fig. 5 is a fragmentary horizontal section taken on the line indicated at 5—5 in Fig. 2, and

Fig. 6 is a transverse section through the work guiding and broach bar positioning ring.

The broach holder of the present invention has a tubular body 1 provided with an enlarged bottom portion 2 provided with holes 3 to receive bolts for attaching it to a floor or other support. The interior of the tubular body 1 is provided with internal cylindrical bearing portions 4 and 5 adjacent the upper and lower ends thereof and with a counterbore 6 at the bottom in which a base 7 fits. The base 7 is secured to the tubular body 1 by means of bolts 8 and has a central projecting portion 9 that fits within the lower cylindrical portion 5 of the housing. The base 7 is provided with a central opening 10 through which the work may be passed and the top face

2

thereof is provided with radial grooves 11 which are equiangularly spaced around the central opening 10. The radial grooves 11 have bottoms 12 that slant outwardly from the central opening 10.

Within the tubular body 1 above the base 7 there is mounted a follower 13 which has external cylindrical bearing portions 14 and 15 at its upper and lower ends which have a sliding fit within the cylindrical bearing portions 4 and 5 of the tubular body 1. The tubular body 1 has an internally threaded portion 16 and the follower 13 has an externally threaded portion 17 that screws into the threaded portion 16 of the body. The follower 13 is moved axially within the tubular body 1 upon turning movement by means of its threaded engagement with the tubular housing. The follower 13 has an upwardly tapering conical interior 18 which serves to position a series of vertically disposed upwardly tapering broach bars 19. Each of the broach bars 19 has cutting teeth 20 along its inner edge and is provided with a straight slanting outer edge 21 that engages the interior 18 of the follower. Each of the bars 19 has a lower end that fits in one of the grooves 11 and the lower ends of the bars 19 are slanted to conform to the slanting bottoms 12 of the grooves 11.

The tubular body 1 is provided with a window 23 and the follower 13 has a series of angularly spaced sockets 24 which are adapted to receive a suitable tool for imparting turning movement to the follower and which are close enough together so that one or more of the sockets is always accessible through the window 23. The exterior surface of the follower 13 is provided with a circumferential graduated scale 25 that moves past a stationary pointer 26 on the bottom of the window 23. Vertical adjustment of the follower 13 serves to impart radial adjustment to the broach bars 19 and since the vertical adjustment of the follower is proportional to its angular movement, the scale 25 serves to indicate the amount of radial movements imparted to the broach bars. The broach bars 19 are clamped between the base 7 and a cap secured to the upper end of the tubular body 1. The cap has an annular body portion 27 that is positioned upon the upper end of the body 1 by means of a dowel pin 28 and which is secured to the upper end of the tubular body 1 by means of attaching bolts 29.

The cap body 27 has a central opening 30 that is provided with a counterbore 31 in which a suitable work guiding ring 32 is mounted. The

guide ring 32 also serves to position the broach bars 19 and is provided on its under side with radial bar receiving slots 33. The exterior of the ring 32 has vertical slots 34 that form continuations of the bar receiving slots 33 and follower blocks 35 are slidably mounted in slots 34. In order to facilitate the assembly of the guide ring and blocks 35 in the cap, a retaining ring 36 is provided which encircles the ring 32 and holds the blocks 35 in the slots 34, the ring 36 being a spring ring which seats in a circumferential groove in the ring 32 and in vertically elongated recesses 38 in the outer sides of the blocks 35. The elongated recesses 38 permit the blocks 35 to have vertical movement in the slots 34 and these blocks are utilized to transmit clamping pressure to the upper ends of the broach bars 19.

The guide ring 32 is held in proper angular position with respect to the annular cap body 27 by means of radially disposed keys 39 that fit in radial slots 40 formed in the body 27 and which project into slots 34 of the ring 32, each of the keys 39 being attached to the body 27 by means of a bolt 41. An annular clamping ring 42 is secured to the annular body 27 by means of bolts 43 and is provided with a recessed under face 44 overlying the follower blocks 35. A cushioning ring 45 is seated in the recess 44 and is interposed between the upper ends of the blocks 35 and the clamping ring 42. The upper ends 46 of the broach bars 19 slant inwardly and the followers 35 have slanting lower ends 47 that fit the slanting ends 46 of the broach bars.

Clamping pressure exerted against the oppositely slanting ends 22 and 46 of the broach bars 19 serves to clamp the bars 19 tightly against the conical interior 18 of the follower 13, which provides a rigid backing for the broach bars during the passage of a work piece through the holder. The elastic cushioning ring 45 is adapted to yield when the bars 19 are simultaneously moved radially inwardly by downward movement of the follower 13 so that adjustments of the cutter bars may be made without releasing the bar clamping elements. The broach bars may be assembled in the holder and clamped in place with the cutting teeth at a slightly greater distance from the central axis than required for cutting the splines to full depth, after which the bars may be accurately adjusted to cut to the desired depth by turning the follower 13. When the bars are resharpened the removal of stock from the toothed edges of the bars can be compensated for by a radial adjustment of the bars. The bars may also be simultaneously adjusted inwardly for a finishing cut.

It is to be understood that variations and modifications of the specific device herein shown and described for purposes of illustration, may be made without departing from the spirit of the invention.

What I claim is:

1. An adjustable broach holder comprising a tubular body, a base and a cap attached to opposite ends of said body and each provided with a central opening and positioning slots radiating from its central opening, broach bars having their ends fitting in said cap and base slots, said bars having toothed inner edges and slanting outer edges, an annular follower within said tubular body and engaging the slanting outer edges of said bars, and means for adjusting said follower axially of said body to radially adjust said bars.

2. An adjustable broach holder comprising a tubular body, a base and a cap attached to opposite ends of said body and each provided with a central opening and positioning slots

5 radiating from its central opening, broach bars having their ends fitting in said cap and base slots, said bars having toothed inner edges and slanting outer edges, an annular follower within said tubular body and engaging the slanting outer edges of said bar, means for adjusting said follower axially of said body to radially adjust said bars, and means carried by said cap and base for clamping said bars and for exerting a radial outward thrust on said bars to hold them 10 in engagement with said follower.

3. An adjustable broach holder comprising a tubular body, a base and a cap attached to opposite ends of said body and each provided with a central opening and positioning slots radiating

20 from its central opening, broach bars having their ends fitting in said cap and base slots, said bars having toothed inner edges and slanting outer edges, said bars having oppositely slanting inwardly converging end faces, an annular 25 follower within said tubular body and engaging the slanting outer edges of said bars, means for adjusting said follower axially of said body to radially adjust said bars, and means for applying clamping pressure to the slanting ends of 30 said bars to hold the same against the interior of said annular follower.

4. An adjustable broach holder comprising a tubular body having internal screw threads, a cap and a base attached to opposite ends of the 35 body and each having a central opening and slots radiating from its opening, a tubular internally conical externally threaded follower screwed into said body and axially adjustable therein, and longitudinally tapering broach bars 40 clamped between said cap and base with their ends guided for radial movements in said slots and their outer edges bearing against the conical interior of said follower.

5. An adjustable broach holder comprising a 45 tubular body having internal screw threads and provided with a window, a tubular internally conical externally threaded follower screwed into said body and axially adjustable therein, said follower having turning tool sockets accessible through said window, a series of longitudinally 50 tapering broach bars mounted within the follower, and means for holding said bars in spaced relation and against endwise movement with their outer edges in engagement with the conical interior of said follower.

6. An adjustable broach holder comprising a tubular body having internal screw threads and provided with a window, a tubular internally conical externally threaded follower screwed into said body and adjustable axially therein, said follower having turning tool sockets accessible through said window, a series of longitudinally 60 tapering broach bars mounted within the follower, and cap and base members attached to opposite ends of said body and having positioning 65 slots to receive the ends of said bars and engaging the ends of said bars to hold the same with their outer edges in engagement with said follower.

7. An adjustable broach holder comprising a 70 tubular body having internal screw threads and provided with a window, a tubular internally conical externally threaded follower screwed into said body and axially adjustable therein, said follower having turning tool sockets accessible 75 through said window, means for indicating the

angular positions of said follower, a series of longitudinally tapering broach bars mounted within the follower with their outer edges engaging the conical interior of the follower, and means for positioning said bars in angularly spaced relation and for holding them against the interior of said follower.

8. An adjustable broach holder comprising a tubular body having internal screw threads and provided with a window, a tubular internally conical externally threaded follower screwed into said body and axially adjustable therein, said follower having turning tool sockets accessible through said window, a base secured to the lower end of said body below the lower end of the follower, said base having a central opening and grooves radiating from said opening, said grooves having outwardly slanting bottoms, longitudinally tapering broach bars having their lower ends fitting in said grooves and their outer edges bearing against said follower, a cap secured to the upper end of the casing and including a guide ring having radial slots to receive the upper ends of said broach bars, and means carried by said cap for clamping said broach bars against said base and against the interior of said follower.

9. An adjustable broach holder comprising a tubular body having internal screw threads, a tubular internally conical externally threaded follower screwed into said body and adjustable axially therein, a series of longitudinally tapering broach bars mounted within said follower with their outer edges engaging the conical interior thereof, annular members mounted upon opposite ends of said body for positioning and clamping said bars, and elastic cushioning means interposed between one of said clamping members and the adjacent ends of said bars.

10. An adjustable broach holder comprising a tubular body, a base attached to the lower end of said body, said base having a central opening and grooves in its top face radiating from said opening with their bottoms slanting from said central opening, an axially movable tubular follower mounted in said body, said follower having an upwardly tapering conical interior, broach bars mounted in said grooves and having toothed inner edges, said bars having slanting bottom and outer edges that conform to the bottoms of said grooves and the conical interior of said follower, an annular cap attached to the top of said body, said cap comprising an annular member having a central opening and a guide ring for said opening having radial slots that are adapted to receive the upper ends of said bars, vertically slideable blocks in said slots engageable with the upper ends of said bars, a clamping ring attached to the annular member and overlying said slots, and elastic cushioning means interposed between said clamping ring and said blocks.
